DESIGN FOR A BUCKLE

Francesco Benenati, Brooklyn, N. Y.

Application December 10, 1934, Serial No. 54,366

Term of patent 7 years

To all whom it may concern:

Be it known that I, Francesco Benenati, a citizen of the United States, residing in Brooklyn, in the county of Kings and State of New York, have invented a new, original, and ornamental Design for a Buckle, of which the following is a specification, reference being had to the accompanying drawing, forming part thereof.

Figure 1 is a plan view of a buckle embodying my new design.

Figure 2 is end view thereof.

The dominant feature of the present design resides in the ornamental rings disposed medially of the buckle, with two prongs carried by each of said rings and mounted thereon in diametrically opposed relationship.

I claim:

The ornamental design for a buckle as shown and described.

FRANCESCO BENENATI.
